(57) **CLAIM**

The ornamental design for an apparatus for the treatment of hair, as shown.

DESCRIPTION

FIG. 1 is a top, front and left perspective view of my new design;

FIG. 2 is bottom, rear and right side perspective view thereof;

FIG. 3 is a top plan view of FIG. 1;

FIG. 4 is a right side elevational view of FIG. 2; and,
FIG. 5 is a bottom plan view of the design.

The cord is shown partially broken away in the various views to indicate indeterminate length.
